[57] **CLAIM**

The ornamental design for a bedside pouch for television remote control and other implements, as shown and described.

DESCRIPTION

FIG. 1 is a front left-hand (defined from a location in front of the apparatus) perspective view of a bedside pouch for television remote control and other implements showing my invention with an upper flap portion folded down;

FIG. 2 is a front left-hand perspective thereof showing the upper flap portion vertically extended;

FIG. 3 is a front elevation thereof with the upper flap portion folded downward over the front thereof;

FIG. 4 is a rear elevation of thereof with the upper flap portion folded downward over the front thereof;

FIG. 5 is a left-hand side elevation thereof with the upper flap portion folded downward over the front thereof;

FIG. 6 is a right-hand elevation thereof with the upper flap portion folded downward over the front thereof;

FIG. 7 is a top plan view thereof with the upper flap portion folded downward over the front thereof; and,

FIG. 8 is a bottom plan view thereof with the flap portion folded downward over the front thereof.
